Patented May 21, 1918.

INVENTOR

Thomas E. Murray
BY *Paul L. Ferguson*
ATTORNEY

UNITED STATES PATENT OFFICE.

THOMAS E. MURRAY, OF NEW YORK, N. Y.

APPARATUS FOR MAKING METAL CHAINS.

1,267,255.

Specification of Letters Patent. Patented May 21, 1918.

Application filed December 29, 1917. Serial No. 209,380.

To all whom it may concern:

Be it known that I, THOMAS E. MURRAY, a citizen of the United States, residing at New York, in the county of New York and State of New York, have invented a certain new and useful Improvement in Apparatus for Making Metal Chains, of which the following is a specification.

The invention is an apparatus for making metal chains. Each link is first made in two half sections. A completed link is then threaded upon one of said half sections, and then the butt ends of said half sections are electrically welded together. The apparatus comprises electrodes constructed to hold the link sections in suitable grooves in their opposing faces, one of said electrodes having a channel open at both ends for receiving a completed link threaded upon one of said half sections.

In the accompanying drawings—

Figure 1 is an elevation of two chain links, one of said links being in place in the welding electrodes. Fig. 2 shows in perspective one member of the pair of lower electrodes. Fig. 3 shows in perspective one member of the pair of upper electrodes. Fig. 4 is a section on the line α , α and Fig. 5 is a section on the line y , y of Fig. 1.

Similar letters and numbers of reference indicate like parts.

The electrodes are shown at A and B. The lower electrode A is formed of two half sections, one of which is shown in Fig. 2. In the face of each section is a U-shaped groove 1, which is bisected by the central channel 2 which extends vertically through the section and is open at both ends. On the opposite sides of the section are lugs 3 for the reception of the clamping bolts 4, by which the said sections are connected together.

The upper electrode B is also formed of two half sections, one of which is shown in Fig. 3. In the face of each section is an inverted U-shaped groove 5, and on opposite sides of said section are lugs 6 for the reception of the clamping bolts 7.

The chain links are made in half sections C, D which are to be butt-welded together. To this end the lower link section C is placed in the corresponding grooves 1 of the sections of the lower electrode A, and the upper link section D is placed in the

corresponding grooves 5 of the sections of the upper electrode B, the butt ends of the sections C, D then registering. If a preceding link E to that to be made has already been completed, said link is placed in the corresponding channels 2 of electrode A, 60 and is threaded upon the lower half section C of the link to be welded, as shown in Fig. 1, so that said link is suspended upon said lower half section. The bolts 4 and 7 being set up to clamp the link sections 65 in the electrodes, said electrodes are relatively moved to bring the butt ends of the link sections into contact, and the welding current is established. As the metal at the joints becomes plastic, the link sections are 70 pressed together, thus uniting said sections and completing the link.

I claim:

1. An electrical welding apparatus for chain links, comprising two relatively movable electrodes for supporting two U-shaped half link sections with their butt ends in welding contact, each electrode comprising a pair of similar half sections receiving a half link between them, and one of said 80 electrodes having an opening to receive a half link threaded upon one of said half sections, and clamping means for securing together the half sections of each electrode.

2. An electrical welding apparatus for chain links, comprising two block electrodes, each having a U-shaped recess for receiving a U-shaped half link section and relatively movable one to the other, and means for clamping said sections in said electrodes, 90 one of said electrodes being constructed to permit the threading of a half link section upon a previously formed link.

3. An electrical welding apparatus for chain links, comprising two superposed block electrodes, each having a recess for receiving a U-shaped half link section, and one of said electrodes having at right angles to the U-shaped recess therein a recess for receiving a half link section threaded upon 100 a previously formed link, and means for moving said electrodes relatively to one another.

4. An electrical welding apparatus for chain links, comprising two relatively movable electrodes, each electrode comprising a pair of similar half sections, each section having in its face a U-shaped groove, the

said grooves in one electrode being inverted with respect to the grooves in the other electrode, and the ends of the grooves in one electrode registering with the ends of the 5 grooves in the other electrode, the members of the pair of half sections of one electrode having in their faces registering channels open at their ends, extending across the faces of said members and bisecting the U-shaped

grooves therein, and clamping means for securing together the half sections of each electrode.

In testimony whereof I have affixed my signature in presence of two witnesses.

THOMAS E. MURRAY.
